US00D581865S

(12) **United States Design Patent**
Koza

(10) **Patent No.:** **US D581,865 S**
(45) **Date of Patent:** **** Dec. 2, 2008**

(54) **SOLAR POWER SUPPLY**

(75) Inventor: **Michelle Koza**, Los Angeles, CA (US)

(73) Assignees: **Sony Corporation**, Tokyo (JP); **Sony Electronics Inc.**, Park Ridge, NJ (US)

(**) Term: **14 Years**

(21) Appl. No.: **29/284,428**

(22) Filed: **Sep. 7, 2007**

(51) **LOC (8) Cl.** **13-02**

(52) **U.S. Cl.** **D13/102**

(58) **Field of Classification Search** D13/102,
D13/103, 184, 199; 136/206, 244, 245; 320/101
See application file for complete search history.

(57) **CLAIM**

The ornamental design for the solar power supply, as shown and described.

DESCRIPTION

FIG. 1 is a perspective view of the solar power supply in the unfolded configuration;

FIG. 2 is a front end view of the solar power supply in the unfolded configuration;

FIG. 3 is a teat end view of the solar power supply in the unfolded configuration;

FIG. 4 is a top plan view of the solar power supply in the unfolded configuration;

FIG. 5 is a left side view of the solar power supply in the unfolded configuration;

FIG. 6 is a bottom plan view of the solar power supply in the unfolded configuration;

FIG. 7 is a right side view of the solar power supply in the unfolded configuration;

FIG. 8 is a perspective view of the solar power supply in the folded configuration;

FIG. 9 is a front end view of the solar power supply in the folded configuration;

FIG. 10 is a left side view of the solar power supply in the folded configuration;

FIG. 11 is a rear view of the solar power supply in the folded configuration;

FIG. 12 is a right side view of the solar power supply in the folded configuration;

FIG. 13 is a bottom edge view of the solar power supply in the folded configuration; and,

FIG. 14 is a top edge view of the solar power supply in the folded configuration.

The broken lines showing the trademark name “Sony” is unclaimed environment and forms no part of the claimed design.
